FLUSHING CISTERNS

Joseph Leslie Pegler, Beecroft, near Sydney, New South Wales, Australia, assignor to Lockair Pty. Limited, Sydney, New South Wales, Australia, a corporation of New South Wales

Application March 27, 1951, Serial No. 217,707
In Australia December 15, 1950

7 Claims. (Cl. 4—43)

1

This invention relates to cisterns of the type that are adopted for the flushing of water closets and the like.

The modern trend is to adopt cisterns of the low-level type; that is to say the kind which can be installed conveniently just above and to the rear or side of the toilet bowl. Such a location has the advantage that they can be attended to conveniently when any adjustment is necessary; it effects a saving in the length of piping for feeding flushing and draining purposes, and at the same time allows of a cistern being let into the wall of the closet at a convenient height.

These low-level cisterns are usually operated by a short hand lever, or the like, but some of the better class cisterns are operated by a push-button set in the wall of the closet close to the toilet bowl.

The present invention has reference more particularly to low-level cisterns of the type operated by a push-button though it is applicable also to cisterns of the overhead type operated by such means; and in some cases the cistern may be operated by a hand controlled valve instead of a push-button.

Primarily the invention aims at providing a flushing unit which can be fitted into a reservoir intended for an overhead or low-level cistern and which, if desired can be substituted for the existing flushing means, should such means prove unsatisfactory in use.

According to a preferred practical application of the invention as suitable for an overhead or low-level cistern of the push-button type the aforesaid unit comprises, in the main a flushing-bell intended to be supported over the orifice in a discharge fitting in the floor of the reservoir, a float-valve movable within said bell and designed to keep said orifice normally closed; and, exteriorly of said bell and in communication therewith, means for providing a water-seal, means for reforming said water-seal after each flushing operation, and means for initiating said flushing operation.

In order however that the invention may be fully understood and readily carried into practical effect reference is now made to the accompanying drawings wherein:

Figure 1 shows a longitudinal vertical section of a cistern embodying the improved flushing unit in its preferred form and as arranged for operation by a push-button;

Figure 2 shows a sectional plan of the outlet fitting of the cistern, taken on the horizontal plane 2—2 of Figure 1; and

Figure 3 is an enlarged central vertical section

2

of the flushing unit appearing in Figure 1, the float-valve therein being illustrated in elevation.

The cistern illustrated is suitable for installation at either a high or low level.

5 The flushing-bell 10 can consist of a device much in the form of an inverted cylindrical canister, and in the example illustrated is supported by arms 11 cast integral with the discharge fitting 12. The flushing-bell 10 is thus held with its mouth 13 a little above the floor of the reservoir 14. The discharge fitting 12 is secured in said floor by means of nut 15, a resilient washer 16 being interposed between flange 17 of the discharge fitting 12 and the floor of the reservoir 14.

10 Alternatively, in an arrangement not illustrated, the flushing-bell 10 could be supported by feet designed to stand upon and be secured to the floor of the reservoir 14, or said flushing-bell 10 could have a plurality of relatively large apertures formed in its wall near to its mouth 13 and have the rim of its mouth 13 affixed to the floor of the reservoir 14.

15 One or more air admitting holes 18 (Figure 3) are provided near the mouth 13 of the flushing-bell 10 to facilitate operation of the flushing-unit in a manner clear from the following description.

20 Within the flushing-bell 10 is a float-valve 19 which can be in the form of an airtight canister loaded with ballast of any convenient type, or sufficiently heavy in itself, and this float-valve 19 has affixed to its bottom a valve head 20 intended normally to be held closely on seat 21 of the discharge fitting 12 under weight of the float-valve 19, there to effectively prevent contents of the reservoir 14 from flowing down said fitting 30 until flushing is implemented.

25 Exteriorty of the flushing-bell 10 there is a two-part cup 22 constituting a receptacle 23 and a compartment 24 (see Figure 3). This compartment 24 is placed in communication with the upper regions of the flushing-bell 10 by means of a tube 25. The compartment 24 is also in communication with limb 26 of a vertical U tube 27 the other limb 28 of which terminates at or about the normal water level in the reservoir 14, which level is indicated by the broken line 29 in Figure 1.

30 Also in communication with the compartment 24 there is a vertical tube 30 which depends almost to the bottom of reservoir 14 and is there closed. Within this tube 30 there is a refilling tube 31 which extends from the receptacle 23 to the lower precincts of tube 30. This tube 30 together with receptacle 23 serves as a trap to retain sufficient water to re-establish a water-seal in the U tube 27 after each flushing operation.

The limb 28 of U tube 27 preferably has a crimped wire 32 in it. In practice it has been found that such a wire will prevent the formation of an air lock in limb 28. Connected to limb 28 there is a tube 33 which extends upwards and over or through the wall of reservoir 14 from which it is led downwards to a wall-fitting (see Figure 1) including a push-button 34 and diaphragm 35 as provided in existing installations of the push-button type.

It has also been found in practice that the presence of a small bleed-hole (not shown) in limb 28 just below the maximum water level in reservoir 14, tends to facilitate operation of the invention.

Filling of the cistern is preferably under control of a ball-float valve of the usual type and not indicated in the accompanying drawings.

Operation of the invention

When first installed it is necessary to form a water-seal in the U tube 27 and to fill the trap, constituted by the vertical tube 30 and the receptacle 23, by priming the refilling tube through the medium of receptacle 23. When this has been done the cistern is ready for operation.

As water enters the reservoir 14 through the usual float-controlled valve (not indicated) it—the water—compresses air in the flushing-bell 10 while float-valve 19 remains seated under its own weight.

The water, continuing to rise in reservoir 14, then completely fills receptacle 23 and ultimately reaches the maximum level determined by the aforesaid usual float-controlled valve.

While the water is rising in reservoir 14 and compressing air in the flushing-bell 10 it necessarily depresses the column of water in limb 28 of U tube 27. This means that a column of water is forced upward in limb 28 of U tube 27.

Now when diaphragm 35 is pressed inwards under pressure of push-button 34 it forces water out of tube 33 into limb 28 of U tube 27 causing the level of water in limb 28 to rise. Some of this water will be ejected into reservoir 14 through the extremity of limb 28.

Immediately pressure on push-button 34 is released water will be sucked into tube 33 and consequently the level of water in limb 28 of U tube 27 would tend to drop slightly. As soon as this occurs the main body of water in the reservoir 14 will exert its superior force and, through the medium of air compressed in flushing-bell 10 will eject water from the U tube 27 into reservoir 14. This allows air entrapped in flushing-bell 10 to pass down through tube 25, through compartment 24 and thence down limb 26 and up through limb 28 to atmosphere, forcing water in U tube 27 ahead of it. As the air entrapped in flushing-bell 10 thus escapes water will rise rapidly in said bell, lift float-valve 19 from its seat 21 and allow the main body of water in reservoir 14 to flow through discharge-fitting 12 say to a sanitary bowl below.

As the level of water receding in reservoir 14 approaches the mouth 13 of flushing-bell 10 air forces its way through holes 18 and rising to the upper precincts of the bell 10 allows the water to be discharged therefrom.

Concurrently with the flushing operation, as just explained, water in the receptacle 23 will flow down refilling tube 31 and then up through tube 30 into compartment 24 of cup 22, and from there it will flow downwards again into U tube 27

27 thus re-establishing the water-seal therein in readiness for a subsequent flushing operation.

In an alternative construction of the improved flushing unit (not illustrated) the cup 22 may be arranged in limb 28 of U tube 27. In this alternative form there would be a bleed-hole in limb 28 in the lower regions of cup 22 and another bleed-hole in limb 28 just below the bottom of the cup. This alternative construction would allow the refilling tube 31 and tube 30 to be dispensed with.

Also in some cases the push-button 34 with its diaphragm 35 and associated pipe 33, together with the refilling and sealing means could be eliminated by fitting a small control cock on the upper extremity of a tube communicating with the upper regions of the flushing-bell 10.

I claim:

1. A flushing unit for water closets and the like comprising a discharge fitting intended to be secured in the floor of the reservoir of a cistern, a flushing-bell supported over said discharge fitting, a float-valve within said flushing-bell and arranged normally to prevent the passage of water through said discharge fitting, a cup supported exteriorly of said flushing-bell and comprising a receptacle with a compartment below, a pipe establishing communication between said compartment and the upper precincts of said flushing-bell, a U tube having one limb in communication with said compartment and its other limb projecting above the mouth of said cup, and means for breaking said water seal by expelling water from said other limb.

35 2. A flushing unit for water closets and the like as claimed in claim 1 characterised in that said cup is constructed in two separable parts, the upper of which constitutes said receptacle.

3. In a flushing unit for the cisterns of water closets and the like wherein air entrapped in a bell over a discharge fitting in said cistern is prevented from escaping by a water-seal established exteriorly of said cistern, means in the form of a receptacle and two concentrically mounted vertical tubes for entrapping sufficient water to re-establish said water seal after each flushing operation.

4. A flushing unit for water closets and the like comprising a discharge fitting intended to be secured in the floor of the reservoir of a cistern, a flushing-bell supported by and over said discharge fitting, a weighted float-valve within said flushing-bell and arranged normally to prevent the passage of water through said discharge fitting, a priming cup supported exteriorly of said flushing-bell and comprising a receptacle with a compartment below, a pipe establishing communication between said compartment and the upper precincts of said flushing-bell, a U tube having one limb in communication with said compartment and its other limb projecting above the mouth of said cup, means depending from said cup for providing a water seal in said U tube, and a push-button and diaphragm exteriorly of said reservoir in combination with a tube connected to said other limb for expelling water from said other limb and thereby breaking the water seal in said U tube.

5. In a flushing unit for water closets, as claimed in claim 4, a crimped wire in said other limb of said U tube to prevent the formation of an air lock therein.

6. In a flushing unit for the cisterns of water closets and the like, a single flushing-bell supported over a discharge fitting in said cistern, a

float-valve contained within said flushing-bell and arranged normally to close said discharge fitting, a water-seal including a priming cup supported exteriorly of said flushing-bell to prevent escape of air from the latter, said priming cup having a lower compartment in communication with the upper precincts of said flushing-bell and means for re-establishing said water seal automatically after each flushing operation.

7. A flushing unit for water closets and the like comprising a discharge fitting intended to be secured in the floor of the reservoir of a system, a flushing-bell supported over said discharge fitting, a float-valve within said flushing-bell and arranged normally to prevent the passage of water through said discharge fitting, a cup supported exteriorly of said flushing-bell and comprising a receptacle with a compartment below, said cup being constructed of two separable parts the upper part of which constitutes the receptacle while the lower part cooperates with the bottom of the first part to provide the compartment, a pipe establishing communication between said compartment and the upper precincts of said flushing-bell, a U tube having one limb in com- 25

munication with the compartment and its other limb projecting above the mouth of the cup, means depending from said cup for providing a water-seal in said U tube, a crimped wire in said other limb of said U tube to prevent the formation of an air lock therein, and a push button and diaphragm exteriorly of said reservoir in combination with a tube connected to said other limb for expelling water from said other limb and thereby breaking the water-seal in said U tube.
